CLAIM

I claim the ornamental design of an edible cake, substantially as shown and described.

DESCRIPTION

FIG. 1 is a front perspective view of an edible cake in accordance with the present invention;

FIG. 2 is a front view of the edible cake in FIG. 1;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines illustrating the candle in FIGS. 1-6 are environment, while the remaining broken lines in FIG. 1-6 illustrate portions of the edible cake that form no part of the claimed design.

1 Claim, 7 Drawing Sheets(56)
